UNITED STATES PATENT OFFICE.

THOMAS B. WREN, OF MAHANOY CITY, PENNSYLVANIA.

GRATE BAR.

Application filed October 8, 1924. Serial No. 742,370.

The invention relates to grate bars of the type used in furnaces and the like, and has for its object to provide a device of this character having its upper side provided 5 with a longitudinally disposed groove and its under side with a longitudinally disposed downwardly extending flange for reinforcing and strengthening the bar. Also to provide the bar, adjacent its ends, with short 10 downwardly extending flanges for stiffening the bar and further bracing the same against sagging, incident to intense heat.

A further object is to provide the bar with a plurality of tapered apertures having their 15 wide ends downwardly disposed, and through which apertures air passes to the bed of coal on the grate, and the small ends of the apertures being relatively small will not become clogged, and prevent the free 20 passage of air therethrough.

A further object is to provide the sides of the grate bar with semicircular shaped apertures, which apertures, when the grate 25 bars are placed in engagement with each other, form air passages similar to the air passages through the body of the grate bar.

With the above and other objects in view the invention resides in the combination and arrangement of parts as hereinafter set 30 forth, shown in the drawing, described and claimed, it being understood that changes in the precise embodiment of the invention may be made within the scope of what is claimed without departing from the spirit of the invention.

In the drawing:—

Figure 1 is a top plan view of the grate.

Figure 2 is a vertical transverse sectional view taken on line 2—2 of Figure 1.

Figure 3 is an enlarged bottom plan view of one end of the grate.

Figure 4 is a longitudinal sectional view through one end of a grate, showing the air passages or apertures in inverted form.

Figure 5 is an end view of the grate shown in Figure 4.

Referring to the drawing, the numeral 1 designates an elongated grate bar adapted 5 for use in furnaces and the like, and 2 a downwardly extending longitudinally disposed relatively wide flange carried by the under side of the grate bar for bracing the same, and preventing the bar from sagging incident to intense heat. Disposed at opposite sides of the flange 2 adjacent the ends of the grate bar are relatively short reinforce-

ing ribs 3, which additionally brace the bar and prevent sagging thereof. It will be noted by providing the flange 2, and ribs 3, said flange and ribs are remote in relation to 60 the upper side of the grate bar, consequently the intense direct heat is more or less dissipated before it reaches the flange and ribs, therefore sagging or breaking of the grate bar is reduced to a minimum. It has been 65 found, by providing the longitudinally disposed groove 4 in the upper side of the grate bar, in registration with the brace 2 on the under side of the grate bar, the grate bar is 70 additionally braced, and at the same time considerable material is saved. Extending vertically through the grate bar is a plurality of tapered apertures 5, which apertures have their small ends upwardly disposed, and of a diameter sufficiently small to 75 prevent particles of coal from falling into the apertures and clogging the same. The apertures, by being tapered, form funnel shaped members, through which the air passes and is discharged into the fire bed, 80 therefore a more perfect combustion is obtained within a fire box.

Referring to Figures 3 and 4 wherein a modified form is shown, the construction is substantially the same as that shown in Figure 1, however the tapered apertures 5^a have their wide sides upwardly disposed. This form of grate may be used where relatively large coal is used, otherwise the construction and operation is the same as that set forth 90 in Figure 1. The longitudinal sides 6 of the grate are provided with semicircular shaped recesses 7, which recesses, when grates are placed side by side in engagement with each other, will form apertures similar in shape 95 and size to the apertures 5 in the main body of the grate, consequently the entire grate surface in a furnace will present a plurality of substantially equally spaced air passages or apertures with the exception of where the 100 grooves 4 are disposed.

From the above it will be seen that a grate bar is provided which is thoroughly braced by ribs and a flange on the under side thereof, remote from the intensive heat, and that air passages are provided through the grate whereby air may easily pass to the fire bed. It will also be noted that by placing the small ends of the tapered apertures 5, at the upper side of the grate, particles of coal of a substantial size will not pass through the apertures and by tapering the apertures as shown 110

in Figure 2 with their large ends downwardly disposed, any foreign matter which may drop into the apertures will not collect therein and will drop through the grate.

5 The invention having been set forth what is claimed as new and useful is:—

The combination with a horizontally disposed grate bar having a plurality of perforations extending vertically therethrough and scattered over substantially the entire surface of the grate bar, downwardly extending transverse integral flanges carried by the ends of the grate bar, a downwardly extending longitudinally disposed and reinforcing rib carried by the underside of

the grate bar and connecting the transversely disposed flanges, of short longitudinally disposed reinforcing ribs formed integral with the under side of the grate bar and the transversely disposed flanges in parallel relation to the first mentioned longitudinally disposed rib and spaced inwardly from the opposite sides of the grate bar and disposed between perforations in the grate bar whereby a free circulation of air is obtained at opposite sides of the short ribs for substantially their full length. 20 25

In testimony whereof I have signed my name to this specification.

THOMAS B. WREN.
